UNITED STATES PATENT OFFICE.

THOMAS B. ATTERBURY, OF PITTSBURG, PENNSYLVANIA.

DESIGN FOR A JAR.

SPECIFICATION forming part of Design No. 18,714, dated November 6, 1883.

Application filed October 8, 1883. Serial No. 287,557. Term of patent 3½ years.

To all whom it may concern:

Be it known that I, THOMAS B. ATTERBURY, a citizen of the United States, residing at Pittsburgh, in the county of Allegheny and State of Pennsylvania, have invented and produced a new and original Design for Jars; and I do declare the following to be a full, clear, and exact description of the same, reference being had to the accompanying drawing, forming a part thereof.

The design is shown in the accompanying drawing, in which the jar is viewed in front elevation.

The main body A of the jar flares upward and outward from the base A' to a distance of about one-third of the height of the jar from the base, or to line B, and from thence the sides of the jar are gradually contracted to the neck portion C, from which point the sides again bulge outward with the curvature of nearly a semicircle to form the portion D, which is crowned with a rim, E, which projects slightly beyond the portion remaining above it, (designated by F,) which is screwed 25 threaded to receive the cap or cover.

Encircling the lower portion of the jar, and extending from the base upward to the greatest diameter of the jar, is a number of longitudinal flutes or ribs, a, which increase the 30 bulge of that portion of the jar.

From the neck portion C, and extending

downward on the main body of the jar is a series of narrow longitudinal flutes or ribs, b, smaller than those on the lower portion of the jar, which are not of uniform length, but so arranged as to form a series of scallops around the jar. 35

On the bulge portion of the jar (designated D) are two rows of short ribs or flutes, d, extending around the upper and lower portion 40 of the bulge, forming a beading, said portion of the jar having a central annular plain band, e, between the two beadings.

What I claim, and desire to secure by Letters Patent, is—

The design for jars herein described, consisting of the portion A, having the large longitudinal flutes or ribs extending from the base over that portion which flares upward and outward, and the smaller flutes or ribs 50 which extend from the neck portion downward, and the portion D, having the rim E and the series of short flutes or ribs d, encircling the upper and lower portion of the bulge D, substantially as shown and specified. 55

In testimony whereof I affix my signature in presence of two witnesses.

THOMAS B. ATTERBURY.
